UNITED STATES PATENT OFFICE.

GEORGE L. CONNER AND GEORGE BYRON, OF WILLIAMS, ARIZONA.

HEADLIGHT FOR LOCOMOTIVES.

1,183,857.

Specification of Letters Patent. Patented May 23, 1916.

Application filed August 10, 1914. Serial No. 856,124.

To all whom it may concern:

Be it known that we, GEORGE L. CONNER and GEORGE BYRON, citizens of the United States, residing at Williams, in the county 5 of Coconino and State of Arizona, have invented certain new and useful Improvements in Headlights for Locomotives, of which the following is a specification, reference being had to the accompanying 10 drawings.

This invention relates to certain improvements in headlights for locomotives and the object of the invention is to provide a device of this general character having novel 15 and improved means whereby the reflector may be automatically adjusted whereby the rays of light will accurately follow the curves of the track.

The invention consists in the details of 20 construction and in the combination and arrangement of the several parts whereby certain important advantages are attained and the device is rendered simpler, less expensive and otherwise more convenient and 25 advantageous for use, all as will be herein-after more fully set forth.

The novel features of the invention will be carefully defined in the appended claims.

In order that our invention may be the 30 better understood, we will now proceed to describe the same with reference to the accompanying drawings, wherein—

Figure 1 is a vertical section taken 35 through a headlight constructed in accordance with our invention; Fig. 2 is a sectional view taken on the line 2—2 of Fig. 1; Fig. 3 is a view in rear elevation of the device as herein shown in Fig. 1; with certain of the parts omitted; and Fig. 4 is a 40 sectional view on the line 4—4 of Fig. 1.

As disclosed in the accompanying drawings, 1 denotes a lamp casing or housing adapted to be properly mounted upon a locomotive, the forward face of such casing or 45 housing 1 being open and adapted to be inclosed by the transparent cover 2, herein shown as semi-circular in cross section for purposes which will be obvious. This transparent closure 2 is adapted to be detachably 50 maintained in operative position and for this purpose the free edge portions of the sides of the housing or casing 1 are provided with the guides or tracks 3—3 adapted to accommodate the marginal portions of 55 such cover 2, said cover being capable of re-

moval upon the release of the top 1^a of the casing or housing 1.

Supported by the top and bottom of the housing or casing 1 and mounted for movement on a vertical axis is a lamp support 4 60 herein shown as of an arc type. The details of the lamp form no particular part of the present invention other than that the reflecting member or plate 5 positioned to the rear of the carbon 6 is adapted to move with 65 the axial adjustment of the lamp and for that purpose we provide such reflecting member or plate 5 at the substantial centers of its upper and lower margins with the inwardly directed arms 7—7 having produced 70 in their extremities the openings 8 angular in cross section and through which are adapted to be positioned the carbon holders 9 of a form in cross section similar to the openings 8 whereby it will be seen that upon 75 rotative movement of the lamp the reflector will be correspondingly moved in unison therewith.

In order to effect the proper rotative movement of the lamp, we affix, as herein disclosed, to the upper carbon holder 9 an 80 end of a rock arm 10 horizontally disposed and projecting exteriorly of the casing or housing 1 through an elongated slot 11 produced in the rear wall thereof. The projected portion 12 of the rock arm 10 is provided with an upstanding lug 14 adapted 85 to be embraced by the annular member 15 produced on the inner end of the elongated member 16 mounted for endwise movement 90 through the upper end portion of the pendulum 17 pivotally supported intermediate its length, as at 19, by the rear wall of the casing or housing 1.

The pendulum 17 is provided intermediate 95 its length with a plurality of openings 20 through which the pivot 19 is adapted to project whereby it will be observed that rotative travel of the lamp or more particularly the reflector thereof may be effectually 100 regulated or controlled. The lower end portion of the pendulum 17 passes beneath a strap or guide member 22 which serves to prevent movement of such lever toward or from the housing 1, as would tend to injure the same which movement would be liable to occur either at the starting or stopping of the locomotive to which our improved device may be applied. The portion 105 of the pendulum 17 below the strap 22 is 110

provided with the weight 23 capable of adjustment lengthwise thereof and being maintained in its adjusted position through the medium of the locking member 24, herein shown as a clamping screw threaded through such weight and adapted to contact with the lever 17 in a manner which is believed to be obvious. In order to further hold the lamp against undue vibration or movement on its pivot, we secure to the rock arm 10 the laterally directed resilient wings 25 herein shown as integrally connected and provided with an inturn portion 26 through which suitable securing means are adapted to pass to hold the same to the arm. These wings are adapted to frictionally engage the adjacent face of the rear wall of the housing or casing 1. In order to maintain the wings 25 in yieldable frictional engagement with the rear wall of the casing we interpose between the lever 17 and nut 27 a coiled spring 28 bearing upon said nut and the lever and disposed about the endwise movable member 16. The spring 28 yieldably permits slight relative movement of the rock arm and pendulum also preventing lost motion. It is also to be observed that the upper extremity of the lever 17 is provided with a plurality of openings 29 through which the endwise movable member 16 is adapted to project and thereby providing a means to compensate for any adjustment of the pivot of such member.

From the foregoing description of our improvements, it is thought to be obvious that a headlight constructed in accordance with our invention is of an extremely simple and comparatively inexpensive nature and is particularly well adapted for use by reason of the convenience and facility with which it may be assembled and of the manifest advantages afforded thereby in having the rays of the light so directed as to follow the curve and it will also be obvious that our invention is susceptible of some change and modification without material departure from the principles and spirit thereof and for this reason we do not wish to be understood as limiting ourselves to

the precise arrangement and formation of the several parts herein shown in carrying out our invention in practice.

We claim:

1. In a dirigible headlight, a casing, a lamp support axially arranged therein, a rock arm connected with said lamp support, the rear wall of said casing having an opening therein through which said rock arm projects, means on the rock arm frictionally engaging the rear wall of said casing to prevent vibration, a pendulum, said pendulum having yieldable connection with said rock arm to prevent rattling of the parts and to tend to maintain said frictional means in operation when the lamp support is moved.

2. The combination with a casing having a lamp support revolvably mounted therein and having a rock arm extending rearwardly thereof, of a pendulum, means yieldably connecting the rock arm and the pendulum, means carried by the rock arm for yieldable frictional engagement with the rear wall of the casing, said yieldable connecting means coating with said friction means to prevent rattling and lost motion of the parts when in use.

3. The combination with a casing having a lamp support revolvably mounted therein provided with a rock arm extending rearwardly thereof through an opening in said casing, a plurality of flexible wings carried by the rock arm to engage the rear wall of the casing adjacent said opening, a pendulum, and a yieldable connection between the rock arm and the pendulum coating with the wings to prevent undue motion and vibration, and assisting in maintaining said wings in snug engagement with the rear wall of the casing.

In testimony whereof we hereunto affix our signatures in the presence of two witnesses.

GEORGE L. CONNER.
GEORGE BYRON.
